UNITED STATES PATENT OFFICE

124,655

DESIGN FOR A COIN BANK

Ralph Victor Moran, Bradford, Pa.

Application September 11, 1940, Serial No. 94,938

Term of patent 3½ years

To all whom it may concern:

Be it known that I, Ralph Victor Moran, a citizen of the United States, residing at Bradford, in the county of McKean and State of Pennsylvania, have invented a new, original, and ornamental Design for a Coin Bank, of which the following is a specification, reference being had to the accompanying drawing, forming part thereof.

In the drawing:

I claim:

The ornamental design for a coin bank, as shown.

RALPH VICTOR MORAN.
